CLAIM

The ornamental design for a valve terminal, as shown and described.

DESCRIPTION

FIG. 1 is a top perspective view of a valve terminal showing my new design;

FIG. 2 is a front view thereof;

FIG. 3 is a rear view thereof;

FIG. 4 is a left view thereof;

FIG. 5 is a right view thereof;

FIG. 6 is a top plan view thereof; and,

FIG. 7 is a bottom plan view thereof.

The broken lines in FIGS. 1-7 are included for the purpose of illustrating portions that form no part of the claimed design.

1 Claim, 7 Drawing Sheets(56)
